UNITED STATES PATENT OFFICE

134,317

DESIGN FOR AN AUTOMOBILE

Thomas P. Duncan, Jr., Newport News, Va.

Application November 18, 1941, Serial No. 104,190

Term of patent 3½ years

To all whom it may concern:

Be it known that I, Thomas P. Duncan, Jr., a citizen of the United States, residing at Newport News, in the county of Warwick and State of Virginia, have invented a new, original, and ornamental Design for an Automobile, of which the following is a specification, reference being had to the accompanying drawing, forming part thereof.

Figure 1 is a view in perspective from the front of the automobile embodying my new design.

Figure 2 is a view in side elevation, and Figure 3 is a view in rear perspective.

The dominant features of my design are shown in full lines in the drawing, which is shaded to represent contrasting colors.

I claim:

The ornamental design for an automobile, as shown and described.

THOMAS P. DUNCAN, JR.
